UNITED STATES PATENT OFFICE.

MARTIN E. BRIGHAM, OF PHILADELPHIA, PENNSYLVANIA.

BOX-MAKING MACHINE.

SPECIFICATION forming part of Letters Patent No. 424,953, dated April 8, 1890.

Application filed October 9, 1888. Serial No. 287,682. (No model.)

To all whom it may concern:

Be it known that I, MARTIN E. BRIGHAM, of the city and county of Philadelphia, and State of Pennsylvania, have invented an Improvement in Box-Making Machines, of which the following is a specification:

My invention relates to machines for making boxes; and it consists of certain improvements, which are fully set forth in the following specification and shown in the drawings which accompany it and form a part thereof.

More particularly my invention is intended for forming boxes of a cylindrical shape out of card-board or similar material, and by the improvements herein set out these boxes are constructed with great rapidity and completeness in all particulars. The card-board is fed to a former, where it is rolled into a cylindrical shape, and by stapling mechanism the edges of this tube are secured together. This tube is then pushed off or removed from the former (which immediately operates to construct another similar tube) and is supplied with a bottom, which is glued to the tube, forming a completed box. These operations are performed continuously and with great rapidity, so that my improved machine is capable of a very large output in a limited time. By stapling the side edges of the tube a very firm box is obtained and one that is much less liable than a box with a pasted or glued seam to become loosened.

One of the great advantages of my improvements lies in the fact that the operations of forming, seaming, and capping are all performed automatically upon the same machine without any interruption or delay. The mechanisms by which these different operations are performed are so connected with each other as to operate in perfect accord as to time, so that each successive operation is commenced immediately upon the completion of the preceding one, and while one box is being capped another tube is being formed and stapled, and the work is never interrupted.

In the drawings, Figure 1 is a front elevation of my improved box-making machine. Fig. 2 is a plan view of the same with the stapling mechanism removed. Fig. 3 is a cross-sectional view through the line $x-x$ of Fig. 2. Fig. 4 is a longitudinal sectional view, on an enlarged scale, of the tube-forming cylinder.

Fig. 5 is a cross-sectional view through the line $y-y$ of Fig. 4. Fig. 6 is a view in detail, on an enlarged scale, of the stapling mechanism and holding devices. Fig. 7 is a sectional view, on an enlarged scale, of the bottom-applying mechanism. Fig. 8 is a cross-sectional view of the bottom-feeding tube on the line $z-z$ of Fig. 7. Fig. 9 is a front view, on an enlarged scale, of the tube-holding mechanism. Fig. 10 is a plan view of the wire-feeding devices. Fig. 11 is a perspective view of a box made by my improved machine; and Fig. 12 is a side elevation of a portion of the stapling devices, illustrating the operation of the staple-forming blocks.

A is the main frame or body of the machine.

B is a forming-cylinder for making the card-board tubes, and has a spring-head C loosely journaled thereto upon a bearing c, so that the tube-forming cylinder B may rotate without carrying with it the spring-head C. Arranged close to the spring-head C are the holders D D, guided in the frame A and adapted to be brought toward each other by means of cams d to clamp the card-board tube supported upon the spring-head C.

The spring-head C is loosely journaled upon the bearing c, so that the card-board tube may be held motionless thereon while the cylinder B is rotating to form another tube. The cams d are connected by links D' with the lever D², which is pivoted at E with the segment F. This segment F is connected to an extension f of the eccentric G, which is operated by the shaft H. Through the eccentric G and segment F the lever D² is operated, and by it, through the links D', the cams d force the holders D D toward each other. A spring d' keeps the upper of the holders normally raised. The shaft H is connected by gearing h with the main shaft H', which is rotated by the driving-wheel H².

The tube-forming cylinder B is provided with a shaft B³, which carries a gear-wheel n, whereby, in the manner hereinafter described, an intermittent revolution is imparted to the cylinder B. Pivoted to the cylinder B is a gripping-jaw b, to which is attached an operating link or ring B', which fits in a hole formed in the cylinder and is free to move therein. A portion of the tube-forming cyl-

inder is cut away to receive the gripping-jaw *b* and present an even surface. Passing through the shaft *B*³ and into the cylinder *B* is a rod *I*, adapted to reciprocate therein. The end of this rod is tapered or conical-shaped at *i* and extends through the ring *B*, which is so suspended from the gripping-jaw *b* that when the rod *I* is projected forward the tapered or pointed end *i*, coming in contact with the ring *B*, forces it down, and thereby depresses the gripping-jaw *b*. The rod *I* is preferably provided with a button upon its end to prevent it being withdrawn from the ring *B*' and to guide the end of the rod beyond the ring. The gripping-jaw *b* is raised or opened to release the completed tube after the rod *I* is reciprocated back by means of a spring *i*³ within the hole or recess of the cylinder *B* acting upon the ring or link *B*'. The reciprocation of the rod *I* to actuate the gripping-jaw is accomplished by means of the pivoted lever *I*' and the rod *I*², the latter of which is caused to reciprocate intermittently in the slide *i*² by means of a cam *I*³, carried by the shaft *II*. A spring *i*' draws the rod *I*² and its connections back into normal position after it has been operated by the cam *I*³. *J* is a stripper surrounding the tube-forming cylinder *B*, with a space between it and the cylinder to receive the card-board tube, and having an open space at the top to expose the lapped edges of the card-board. The end of this stripper preferably does not extend to the end of the cylinder *B*, but leaves a circular rim *B*², about which the edge *x*² of the card-board tube is exposed to receive as it is rotated glue or paste from the tube *M*. A valve *m* may be used to control the flow of glue from this tube. Secured to the other end of the stripper *J* are guide-rods *j*. Pivoted to these guide-rods is the lever *J*', which is in turn pivoted to the rod *J*². The rod *J*² is caused to reciprocate in the slide *j*² by the cam *J*³, carried by the shaft *II*, whereby an intermittent reciprocation is imparted to the stripper *J*. A spring *j*' draws the rod *J*² and its connections back to normal position after actuation by the cam *J*³.

K are feeding-rollers mounted in a standard and geared together, between which the card-board *L*² is fed to the cylinder *B*. These rollers are provided with a cutter *k* to cut the card-board into the proper lengths. The diameter of the feeding-rollers *K* is preferably slightly larger than that of the tube-forming cylinder *B*, so that each rotation of the feeding-rollers *K* will cut the exact length of card-board required, including lapped joint of box-cylinder; but it is apparent that the same result might be accomplished by other means, as by causing the rollers *K* and the cylinder *B* to rotate at different relative speeds or by the use of additional cutters *k*.

L is a guide for the card-board, preferably having a downwardly-curving edge to guide the card-board to the tube-forming cylinder, where it is clamped by the gripping-jaw *b*

and rolled into the tube. The card-board is fed to the cylinder after it has been cut by means of the plate *L*', pivoted on its sides to the guide *L*, terminating in a curved guide for directing the card under the jaw of the tube-forming cylinder. The card-board *L*², fed from the rollers *K* upon the guide *L*, comes in contact with the guide-plate *L*', and as it is fed onward forces the guide-plate up, as shown in Fig. 5. A spring *l*' limits the amount this guide-plate *L*' may be forced up or raised by the card-board, and acts to force the card forward when the jaw is open to receive it.

When the card-board is cut, the jaw *b* is open to receive the card, and as the tension upon the guide-plate *L*' is decreased the spring *l*' forces the plate down, pushing the edge of the card-board forward between the curved edge *l* of the guide *L* to the tube-forming cylinder, where it is seized by the gripping-jaw *b* and rolled into the tube *X*. I prefer this mechanism for feeding the card-board after it has been cut to the forming-cylinder; but it is apparent that any other efficient mechanism might be substituted therefor without departing from the principles of my invention.

K' is a gear-wheel meshing with one of the feeding-rollers *K* and with the gear-wheel *K*², which is journaled in the frame of the machine.

N is a gear-wheel similar to the wheel *K*², also journaled in the frame *A*. The wheel *N* is geared to the wheel *n* on the shaft *B*³, and thereby the rotation is imparted to the tube-forming cylinder. Upon the sides of the wheels *N* and *K*² are a series of projections *N*', arranged at regular intervals.

O are two arms pivoted to an extension upon the cam-slide *P* and adapted to engage with the projections *N*' upon the wheels *N* and *K*². Springs *o* prevent the arms *O* from falling, while allowing them to be depressed. The cam-slide *P* works in guides in the frame *A* and is provided with an opening *P*', in which the cam *P*², carried by the wheel *P*³, works to cause an intermittent to-and-fro reciprocation of the cam-slide *P*. The arms *O* being carried by this slide *P*, engage alternately with the projections *N*' on the wheel *N* and those on the wheel *K*², imparting intermittent rotations to these wheels alternately and through them to the tube-forming cylinder *B* and the feeding-rollers *K* *K*'. The wheel *P*³ and its cam is carried by the shaft *II*'.

R is the stapling mechanism, supported upon the frame *A* immediately above the tube-forming cylinder *B*. These stapling devices, as shown, consist of the hammers *r* and staple-formers *r*², which are respectively connected to operate in unison. The hammers *r* are provided with a roller *r*' and the staple-formers with a roller *r*².

R' is a cam journaled in the frame *A* and adapted to come in contact with the roller *r*' to operate the hammers *r*.

*R*² is a cam also journaled in the frame *A*

and adapted to operate the staple-formers r^2 through the rollers r^3 .

W is a ratchet-wheel secured to the cams R' and R². This ratchet-wheel is operated by

5 a pawl W', carried by the arm R³, pivoted to the lever D², and thereby operated by the eccentric G. When this arm R³ moves forward, it carries the pawl W' forward, engaging with the teeth of the ratchet-wheel W. Then,

10 moving backward through the operation of the eccentric G, it rotates the ratchet-wheel, and thereby the cams R' and R², which are secured to it. Springs r⁵ draw the hammers and staple-formers back to a raised position.

15 Blocks r⁴ are located under the hammers during the operation of the staple-formers, and over which the wires V are fed. The staple-formers press the wire over these blocks in descending, cutting and forming it into staples.

20 When the hammers r descend, these blocks r⁴ are drawn out of the way in the well-known manner, and may be made to return again to position after the hammers ascend.

The particular construction of the stapling 25 device is immaterial, and the details thereof form no part of the present invention.

I prefer to operate the blocks r⁴ in the manner shown in Fig. 12, in which the blocks are supported in guides R², secured to or made a

30 part of the main frame A and normally pressed forward by springs r⁶. The front edges of these blocks are beveled, and the staple-formers r² are constructed with a beveled portion also, which, coming in contact

35 with the beveled edges of the blocks r⁴ after the staple has been formed, pushes the blocks out of the way for the operation of the hammers r. When the staple-formers r² and hammers r⁶ are lifted, the springs r⁶ again

40 press the blocks r⁴ forward into position for the formation of new staples.

The forming-cylinder B is provided with curved depressions b' at the place where the edges of the tube lap, whereby the ends of

45 the staples x may be forced through the lapped edges of the tube and doubled over, as shown in Fig. 11. The wire V is fed under the stapling devices from spools V' on each side by feed-rollers Y. (See Fig. 10.) These feed-

50 rollers are carried on the main frame or frame of the stapling device and are operated through the reciprocations of the stripper or sleeve J by arms Y', pivoted to the ends of a link Y², which is connected by a pivoted link

55 Y³ with the slide J⁴, carried by the guide-rods j. The feeding-wheels Y are provided with ratchets y, with which pawls upon the arms Y' engage to turn said guide-wheels and feed the wire under the stapling mechanism. By

60 the forward reciprocation of the stripper J one set of feed-wheels Y is operated, and by the backward reciprocation the other set receives motion.

S is the bottom-applying holder, consisting 65 of a cylinder provided with an opening s to receive the bottoms X², which are fed thereto, in the manner hereinafter described, from the

feeding-tube T. This cylinder is provided with a rack s', the teeth of which engage with those of the segment F, whereby the bottom- 70 applying holder S is reciprocated.

S² is a plunger within the holder S, adapted to push the bottoms X² upon the tubes X while in the custody of the holders D when the holder S is projected forward. 75

S³ is an arm connecting the plunger S² with the lever D², whereby it is operated.

T is a feeding-tube to contain the box-bottoms X². By means of a stop t these bottoms are allowed to drop one at a time into the 80 bottom-applying cylinder S. The stop t consists of two pins extending through the feeding-tube T in the path of the bottoms, and so arranged that when the one is withdrawn to allow a bottom to fall the other is inserted to 85 prevent the other bottoms from falling also. This stop t operates synchronously with the bottom-applying holder S.

T² is a rod provided with a nut T⁴ at its end. 90

T³ is an upright secured to the plunger S², in which the rod T works, so that when the plunger S² is withdrawn from the cylinder or bottom-applying holder S the upright T³, coming in contact with the nut T⁴, pushes back the 95 rod T and withdraws the lower pin of the stop t, allowing a bottom X² to drop through the aperture S.

T' is a spring to reset the stop t.

Q is a blow-pipe connected with a fan or 100 blower q and located between the holders D D and bottom-applying holder S, by which the boxes when completed are blown out of the way of the mechanism.

U are screws provided on their ends with 105 pieces of rawhide or similar material u, adapted to be brought in contact with the wheels N and K² to create a friction and prevent them accidentally rotating too far or in the wrong direction. Any other friction-creating device may be used. 110

The operation of the machine is as follows: The card-board L² is fed from a roll to the feeding-rollers K and thence to the guide L, lifting the guide-plate L' in the manner heretofore described. When the card-board is cut, the plate L' descends, pushing the edge of the paper between the guide end l to the tube-forming cylinder B, which is started in rotation by the movement of the cam-slide P, 115 carrying the arm O, which operates the wheel N, geared to the gear-wheel n. Simultaneously the rod I² is operated by the cam I³ and the rod I is projected forward, operating the gripping-jaw b in the manner described heretofore. The forming-cylinder, rotating, rolls the card-board into a tube X under the stripper J, leaving the edge x² exposed, which during rotation receives the glue or paste from the tube M. At the instant the tube X has been rolled the arm R³ turns the ratchet W, bringing into operation 120 the stapling mechanism. The cam J³ then operates the rod J², and thereby projects the

130

stripper J forward, which carries the stapled tube forward upon the spring-head C, and the holders D D are at the same time operated by the rods D' and cams d to hold the tube 5 when the bottom-applying holder S is moved forward and the piston S² forces the bottom X² upon the glued edge x² of the tube. The bottom-applying holder then moves back, the holders D D release the box, and it is 10 blown out of the way by the tube Q, and the operation continues as before, all of the parts of the different mechanism being so timed by their relative connections with each other as to perform their functions continuously and 15 without any interruption. While the bottom is being applied to one tube another tube is being formed on the rotating former.

Having now described my invention, what I claim as new, and desire to secure by Letters 20 Patent, is—

1. In a box-making machine, the combination of a tube-former, a feeding device for feeding the card-board to the former, a stapling mechanism for securing the edges of the 25 card-board forming the tube together, and a stripper to push the stapled tube from the former.

2. In a box-making machine, the combination of a tube-former, a stapling mechanism 30 to secure the edges of the card-board forming the tube together, a holder for holding the stapled tube for the application of the bottom, and a stripper to push the stapled tube from the former to the holder.

3. In a box-making machine, the combination of a tube-former, a feeding device for feeding the card-board to the former, a stapling mechanism for securing the edges of the 35 card-board forming the tube together, a bottom-feeding mechanism to feed the bottoms one at a time, a bottom-applying holder, power 40 devices, substantially as set forth, to move the bottom-applying holder to or from the tube-former, a stripper to push the stapled tube from off the former, and holders for supporting the tube during the application of the bottom.

4. In a box-making machine, the combination of a tube-former, a feeding device for 50 feeding the card-board to the former, a stapling mechanism for securing the edges of the card-board forming the tube together, a bottom-feeding mechanism to feed the bottoms one at a time, a bottom-applying holder, 55 power devices, substantially as set forth, to move the bottom-applying holder to or from the tube-former, a stripper to push the stapled tube from off the former, holders for supporting the tube during the application of the bottom, power mechanism to rotate the cylinder-former, reciprocate the stripper, and operate the holders to or from each other, and connecting timing devices between said former, stripper, holders, and bottom-applying holder, 60 whereby they operate in unison and synchronously.

5. In a box-making machine, the combination, with a rotary former to form a tube from a strip of card-board, of feeding-rollers to feed the card-board to said former, a fixed 70 guide to guide the card-board from said feeding-rollers to the former, and a pivoted guide-plate adapted to act in connection therewith to assist the feeding of the card-board to the former.

6. In a box-making machine, the combination of a tube-former with a staple-driving mechanism arranged close to the surface of the former, so as to cause the staples to pass through the lapped edges of the cylinder on 80 the former, connecting power mechanism for driving the staples when the former is stationary, and a stripper for discharging the stapled tubes from off the former.

7. In a box-making machine, the combination of a rotating former to form a tube of card-board, a pair of gripping-holders arranged in front of said former, a stripper to push the tube from said former between 85 said holders, and devices to move said holders toward each other to grip the card-board tube.

8. The combination of a pair of holders for the cylinder or tube with a hollow applying-holder having an aperture for receiving a 95 box-bottom, a plunger for pushing the box-bottom toward the open end of the bottom-applying holder, power mechanism to simultaneously reciprocate both the bottom-applying holder and plunger to or from the cylinder-holders, a bottom-feeding tube, and a stop 100 in said bottom-feeding tube actuated by the plunger to feed the bottoms one at a time to the bottom-applying holder.

9. In a box-making machine, the combination of a rotary former for forming a tube of card-board, having a gripping-jaw, feeding and cutting rolls to feed said card-board toward the former and cut it into lengths, a 105 guide for the card-board between the feeding-rolls and the former, a pivoted guide and feeding plate to feed the card-board when cut to the gripping-jaw of the former, and power mechanism to intermittently and alternately rotate said former and feeding and cutting 110 rolls.

10. The combination of the tube-former B, feeding-rolls K K, gear-wheels N and K², gearing connecting said gear-wheels N and K² with the tube-former and feeding-rolls, respectively, projections N' on said wheels N and K², cam P², and cam-slide P', operated thereby and carrying arms O, adapted to engage with the projections N' alternately upon the wheels N and K² to impart an intermittent and alternate rotation thereto.

11. The combination of the rotating tube or cylinder former having a spring-head loosely journaled thereto, stapling mechanism to secure the lapped edges of the card-board tube 130 or cylinder, a stripper to push the stapled tube from the former upon said spring-head,

- and mechanism, substantially as described, to project said stripper forward when the tube is stapled.
12. The combination of the rotating tube or cylinder former having a spring-head loosely journaled thereto, stapling mechanism to secure the lapped edges of the card-board tube or cylinder, a stripper to push the stapled tube from the former upon said spring-head, holders to support the tube while upon said spring-head, and mechanism, substantially as described, to project said stripper forward when the tube is stapled.
13. The combination of the rotary tube or cylinder former B, stapling mechanism to secure the lapped edges of the card-board tube together, stripper J, guide-rods j, secured thereto, cam J³, and connections with said guide-rods j, operated by the cam J³, to intermittently project the stripper to remove the stapled tube from the former B.
14. The combination of a rotary former for forming a tube of card-board, stapling devices for securing the edges of the card-board together, a stripper to push the card-board tube from the former, holders to support the tube when pushed from the former, and cam mechanism to operate said holders synchronously with the stripper.
15. The combination of a rotary former for forming a tube of card-board, stapling devices for securing the edges of the card-board together, a stripper to push the card-board tube from the former, holders to support the tube when pushed from the former, cam mechanism to operate said holders synchronously with the stripper, a bottom-applying holder, and power devices, substantially as set out, to move the bottom-applying holder to or from the tube-former, and timing mechanism to operate said stripper, holders, and bottom-applying holder simultaneously.
16. The combination of the rotating former B, stripper J, holders D D, bottom-applying holder S, having rack s', segment F, and eccentric G, whereby said bottom-applying holder is moved to and from said holders D D.
17. The combination of the rotating former B, stripper J, holders D D, bottom-applying holder S, having rack s', segment F, and eccentric G, plungers S², connecting-arm S³, and lever D², whereby said bottom-applying holder and plunger are operated synchronously.
18. The combination of the rotating former B, stripper J, holders D D, bottom-applying holder S, plungers S², bottom-feeding tube T, stop t, rod T², connection T³ between said rod T² and plunger S², and power mechanism, substantially as described, to operate said bottom-applying holder, plunger, and stop synchronously.
19. The combination of the rotating tube-former B, staple-formers r², hammers r, cams R' and R², connected together, ratchet W, connected with said cams, and power mechanism, substantially as described, to operate said ratchet and cams.
20. The combination of a rotary tube-former for forming a tube or cylinder of card-board, stapling mechanism for stapling the lapped edges of said card-board tube, a stripper to push the stapled tube from the tube-former, and wire-feeding wheels operated by said stripper to feed the wire under the stapling mechanism.
21. The combination of the rotary tube-former B, stapling mechanism R, stripper J, wire-feeding wheels Y Y and Y Y, guide-rods j, links Y', ratchets y, carried by said wheels Y, link Y², slide J⁴, and connecting-link Y³. In testimony of which invention I hereunto set my hand.
